[57] CLAIM

The ornamental design for a cigar humidor, as shown and described.

DESCRIPTION

FIG. 1 is a diagrammatic perspective view of the cigar humidor in the closed position.

FIG. 2 is a front elevational view of the cigar humidor in the closed position.

FIG. 3 is a rear elevational view thereof.

FIG. 4 is a right side elevational view thereof.

FIG. 5 is a left side elevational view thereof.

FIG. 6 is a top plan view of the cigar humidor in the closed position, the bottom view being a mirror image of the top view; and,

FIG. 7 is a diagrammatic perspective view of the cigar humidor in the open position in full lines with cigars and a hand shown in broken lines representing environmental association matter being for illustrative purposes only and forming no part of the claimed design.
